[57] ABSTRACT

A dispensing device having a pump and pump actuating means, associated with a tank containing a concentrated syrup. The pump and actuating means therefore are constructed so as to be selectively adjustable to discharge a predetermined amount of syrup from the storage tank at each cycle thereof. The discharged syrup is admixed with a diluting liquid in a mixing chamber before discharge to a dispensing cup.

MIXING AND MEASURING ARRANGEMENT FOR BEVERAGE DISPENSER

BACKGROUND OF THE INVENTION

The present invention relates to beverage dispensing devices and more particularly to beverage dispensing devices in which a concentrated syrup is mixed with a diluting liquid such as water or the like.

Dispensing machines of the foregoing type dispense the final product in quantities of one cup at a time. It is essential, therefore, that each cup of final product dispensed have substantially the same ratio of concentrated syrup and mixing liquid to maintain a uniform taste or flavor.

Generally, the dispensing machine includes a storage tank or chamber for the concentrated syrup and a separate storage tank or chamber for water and/or other mixing liquid. The concentrated syrup and water or mixing liquid are controlled to flow in selective quantities into a mixing chamber at the desired ratio for producing the beverage.

Only very recently has a coffee concentrated syrup been made available to the public. Hence, because of the heavy viscosity of the same, a new apparatus had to be invented to use the syrup in dispensing machines. It was because of the foregoing problem that the present invention was conceived and developed.

SUMMARY OF THE INVENTION

By the present invention, it is proposed to provide a new and novel means for adjusting and controlling the quantity of the concentrated syrup for a given amount of mixing liquid so as to maintain a desired ratio and thereby assure that each cup of mixed beverage has substantially the same taste.

It is still another object of the invention to provide a new and novel mixing chamber for mixing the concentrated syrup and the mixing liquid prior to being discharged into a cup or other receiving vessel.

The foregoing and other objects of the invention are accomplished by a dispensing device comprising a storage tank for concentrated syrup. The storage tank includes a conduit having a pressure responsive outlet valve at its lower end. The conduit defines a pump housing and has an adjustable stroke piston means mounted for lengthwise movement therein. The piston means includes piston head means for permitting flow of the concentrated syrup into the pump chamber during upward movement thereof so that at the upper end of the piston travel a predetermined quantity of syrup is retained within the chamber by the outlet valve means at the lower end. The stroke or travel of the piston head means and thereby the pump volume is adjusted by means incorporated in the piston actuating linkage and is arranged to yield the desired volume change at the upper end of the stroke. Further means on the piston head means cuts off the flow from the storage chamber and past the piston during downward movement thereof so that a pressure is exerted on syrup whereby the pressure responsive outlet valve is opened and the syrup is discharged from the storage tank.

The concentrated syrup is discharged in the nature of spray onto a funnel-like or conical plate in a mixing chamber. At the same time, the mixing liquid is also discharged onto the conical plate so that the concentrated syrup and the mixing liquids are premised

thereon. The premixed concentrated syrup and mixing chamber then flow from the mixing chamber into a cup or the like.

The principles of the present invention are adaptable for use with concentrated syrups having different viscosities. Syrups of different viscosity may require mechanical structural modifications to achieve a proper mix of the syrup and mixing liquid. As more fully to be demonstrated hereinafter, the mechanical structure for mixing a less viscous syrup concentrate such as coffee differs from the structure for mixing the thicker more viscous concentrate such as chocolate. However, while these two structures may differ in appearance, the underlying and basic structural principals remain the same.

Further features of the invention will hereinafter appear.

BRIEF DESCRIPTION OF THE DRAWINGS

FIG. 1 is a perspective view of a beverage dispensing machine embodying the measuring end mixing arrangement of the present invention;

FIG. 2 is an enlarged fragmentary perspective view of the measuring and mixing arrangement with the cover plate removed;

FIG. 3 is an enlarged fragmentary perspective view of the mechanism for actuating and varying the stroke of the piston means;

FIG. 4 is a cross sectional view of the measuring and mixing chambers showing the piston on the downward stroke;

FIG. 5 is a cross sectional view taken generally along the lines 5-5 of FIG. 4;

FIG. 6 is an enlarged cross sectional view taken generally along the lines 6-6 of FIG. 3;

FIG. 7 is an enlarged cross sectional view taken generally along the lines 7-7 of FIG. 3;

FIG. 8 is an enlarged cross sectional view taken generally along the lines 8-8 of FIG. 3;

FIG. 9 is an enlarged cross sectional view taken generally along the lines 9-9 of FIG. 3 and showing the condition of piston means during the down stroke;

FIG. 10 is an enlarged cross sectional view taken generally along the lines 10-10 of FIG. 9;

FIG. 11 is an enlarged cross sectional view taken generally along the lines 11-11 of FIG. 4;

FIG. 12 is an enlarged cross sectional view similar to FIG. 9 but showing the condition of the piston means during the up-stroke thereof;

FIG. 13 is an enlarged cross sectional view of the mixing and measuring chambers of another embodiment of the invention particularly adapted for dispensing hot chocolate;

FIG. 14 is an enlarged cross sectional view taken generally along the lines 14-14 of FIG. 13;

FIG. 15 is an enlarged cross sectional view taken generally along the lines 15-15 of FIG. 13;

FIG. 16 is an enlarged cross sectional view taken generally along the lines 16-16 of FIG. 13 showing the piston means at the upper limit of travel thereof;

FIG. 17 is an enlarged cross sectional view similar to FIG. 16 but showing the condition of the outlet valve and piston during the down stroke of the piston means; and

FIG. 18 is an enlarged cross sectional view similar to FIG. 17 but showing the condition of the outlet valve and piston during the up-stroke of the piston.

DETAILED DESCRIPTION OF THE DRAWINGS

Referring now to the drawings there is shown a beverage dispensing machine 10 including a housing or frame 11 in which the usual mechanism for actuating the dispensing mechanism is enclosed. The mechanism includes a motor 20 (see FIG. 3) for operating pumps and drive means for mixing the components from which the beverage is to be made.

The dispensing device 10 shown is adapted for mixing a concentrated solution of syrup or coffee with water. The mixing is performed in a mixing and measuring means generally indicated at 12 located in the forward section of frame 11. The mixing and measuring means 12 includes a storage bowl 13 for storing the concentrated syrup or solution of coffee and a hot water storage bowl W. The bottom of the storage bowl 13 is provided with a conduit 14 defining a pump chamber or cylinder 15 which communicates with the interior of the bowl 13. A pump 16 is operative to discharge the coffee syrup from the conduit 14 in controlled amounts from the storage bowl 13.

A pressure responsive outlet valve 17, FIGS. 4 and 11, is located at the bottom or lower end of the conduit 14. The valve 17 is a cylindrical member 18 made from rubber or the like with a slit 18' extending therethrough and supported by a clamping band 19 disposed to the end of the conduit 14 as shown in FIG. 11. The cylindrical member 18 is formed with a recess 21 defining a circular wall 22 which embraces and is clamped to the conduit 14 by the band 19. The upper end of wall 22 is provided with outwardly extending perimetrical flanges 22' to limit upward movement of the band 19. A cylindrical recess 24 is formed axially in the upper face of the valve 18 communicating with slit 18'.

The pump 16 includes a piston means and an actuating means 27 (see FIG. 3). The piston means comprises, as shown in FIGS. 4, 9, 10 and 12, a piston head assembly 28 including a lower slide head 29. The slide head 29 is of cylindrical cross section and is formed with a circumferential groove 31 having an O-ring 32 seated therein. The O-ring 32 provides a sliding seal along the inner wall of the pump chamber 15. A plurality of spaced passages 33 extend through the slide head 29 to permit flow from the storage bowl 13 as will hereinafter be explained.

An axial bore 33' extends through the head 29 and slidably receives a shaft 36 projecting axially from the under side of a connecting head 35. The shaft 36 is of greater length than the height of the slide head 29 so that the shaft 36 and head 29 are slidable relative to each other. The head 37 of a screw 38 threaded into the free end of the shaft 36 prevents the slide head 29 from being detached.

The connecting head 35 includes a lower cylindrical portion 39 having a bottom face 41 adapted to overlie and close the passages 33 during the downward of feed stroke of the piston head assembly 28 as more fully to be explained hereinafter. The upper part 42 is integrally formed with the cylindrical portion 39 and has an axial extending slot 43 which intersects with a relatively wide open ended bore 44 at its lower end. An oppositely extending radial aperture 45 accommodates the right angled turned end 46 of a piston rod 47 (see FIG. 9). The piston rod 47 is assembled to the head 35 by rotating the entire assembly 28, outside the pump chamber, at right angles and positioning the rod 47 in

the slot 43 with the bent end 47 introduced through the slot 44. The end 46 is then inserted into the radial aperture 45. The piston rod 47 and connecting head 28 are thus turnable relative to each other about a horizontal axis provided by the turned end 46 of the connecting head 28.

As shown in FIGS. 2, 3 and 6-9, inclusive, the piston rod 47 is connected to the pump actuating means 27 for reciprocating the piston head assembly 28 within the pump chamber or cylinder 15. The pump actuating means 27 includes a drive motor 20 having a cam 48 fixed to the motor shaft 49 for rotation therewith. Eccentrically connected to the cam is one end of connecting rod sub-assembly 52. The connecting rod sub-assembly 52 includes a bearing block 51 which is eccentrically connected to the cam by a pin 53. A sleeve shaft 54 is fixed at one end in the block 51. A rod 56 is slidably disposed in the sleeve 54 with the upper end of the rod being secured to a connecting bushing block 57. The upper end of the bushing block 57 is pivotally connected to an adjustment sleeve 58 by a pin 59 through the C-clamp 61 fixed on the sleeve 58. Extending between the bushing blocks 57 and 51 so as to yieldably maintain the rod 56 within the sleeve 54 is a compression spring 62, the upper end thereof being held by a screw 57' anchored to block 57 while the lower end thereof is similarly anchored by screw 51' in block 51 (see FIG. 6).

The adjustment sleeve 58 is frictionally held on rock arm 63 which is connected at one end to a rock-shaft 64 journaled in a sleeve 64' which is mounted to a bracket 66 which is fixed to the housing 11. An adjustment lever 67, having an offset, is pivotally connected at one end to the sleeve 58 by means of a C-clamp 68 and a screw 69 so that the C-clamp is fixed. The other end of the adjustment lever 67 is provided with a pin or lever 70 which is seated in slot 71 in plate 11' to ride therein for sliding movement therein horizontally. The offset on lever 67 is provided because the medial portion lies in front of the C-clamp 61 and the bushing 57. The stroke of the piston rod 47 will be varied by positioning the sleeve 58 relative to the rod 63. This is accomplished by moving the pin either to the right or left.

The position of the adjustment sleeve 58 on the rock arm 63 also positions the location at which the connecting rod 56 is operative to rock the arm 63. If the sleeve 58 is moved closer to the rock shaft 64 to provide a shorter lever arm length, the connecting rod assembly 53 is operative to increase the degree of angular turning of the rock shaft 54 upon rotation of the cam 48. Positioning of sleeve 58 further from the rock shaft 54 causes a longer lever arm and a decrease in the angular turning of the rock shaft. The positioning of the connection of the connecting rod 56 at different locations along the length of the rock arm 63 is made possible by the lengthwise yieldable structure of the connecting rod sub-assembly 52 described above.

A second rock arm 76 is fixed to the other end of the rock shaft 64 to be rocked thereby. The second rock arm 76 includes an aperture at the free end which receives the turned end 76' of the piston rod 47. The piston rod 47 is held attached by a pivotally connected clamping plate 77 which overlies the turned end as shown in FIGS. 3 and 8. One end of the plate 77 is offset at 77' and pivotally secured to the arm 76 at the other end by a pin 77''. A positioning plate 77''' on plate 77 lies on the upper edge of arm 76 (see FIG. 3).

A mixing chamber means 78 is located below and aligned with the pump chamber 15. The mixing chamber means 78 includes a bowl 79 supported on the frame 11 and has an outlet nozzle 80 projecting from the base. A conical mixing plate 81 having an axial opening 82 is detachably mounted on the bowl 79 by an integral hook-shaped strap 83. The axial opening 82 is aligned with the outlet nozzle 80 and the pump chamber 15 on the syrup storage tank 13.

A nozzle 84 connected to a suitable source of mixing liquid, such as hot water, is supported on the bowl 79 to direct a stream of hot water tangentially on the conical plate 81. The water is discharged at a predetermined period which is controlled by the energization of a micro-switch 86 riding on cam 48 (see FIG. 3).

In operation, the pump 16 is adjusted so that the piston head assembly 28, when at the end of its stroke or raised to its maximum elevated position, provides the desired volume of coffee syrup for mixing with the hot water. The desired volume of the pump 16 is achieved by selectively positioning the adjustment sleeve 58 on the adjustment rock arm 56 to control the degree of angular turning of the rock shaft 64 and thereby the length of travel of the piston head assembly 28 imparted by the second rock arm 76.

It is to be noted, as shown in FIG. 12, that when the piston head assembly 28 is in its upper position, the lower slide head 29 is spaced from the connecting head 35 so that the coffee syrup is free to flow through the passages 33 into the chamber. Upon downward movement of the piston head assembly 28, the slide head 29 is contacted by the lower face of the upper head 35 and forced downwardly by the head 35 whereby to overlie the entrance to the passages 33 and whereby a pressure force is applied to the coffee syrup in the pump chamber 15 below the sliding head and in the lower end thereof and in the recess 24. As the pressure on the syrup within the pump chamber 15 is increased, the slit 18' is opened to provide an outlet for the coffee syrup to be discharged at a pressure from the opening and deposited on the face of the conical mixing plate 81. At the same time, hot water is simultaneously discharged from the nozzle 84 on the plate causing a swirling action to pre-mix of the coffee syrup and hot water on the conical plate 81. The pre-mixed beverage is discharged through the small outlet 82 and to the aligned outlet 80 into a cup or the like.

When the coffee syrup has been discharged from the pump chamber 15, the piston head assembly 28 reverses and moves upwardly. During upward movement, no downward pressure is applied on the valve 17 so that the latter closes and prevents liquid flow therethrough. As the piston head assembly 28 moves upwardly, the slide head 29 assumes the position shown in FIG. 12 so that the coffee syrup in the storage bowl 13 is free to flow through the passages 33 into the pump chamber 16. When the piston head assembly 28 reaches the upper limit of travel, the pump chamber 16 is filled with desired amount of syrup for a repeat of the mixing with the water in the manner heretofore described upon downward movement of the piston assembly.

Referring now to FIGS. 13-18, there is shown another embodiment of pump arrangement 110 which may be used in practicing the invention. This embodiment of the invention is particularly adaptable for use in mixing hot chocolate. The pump arrangement 110

includes generally a pump housing 111 and a piston head assembly 112.

The pump housing 111 depends axially from the storage tank 113 and communicates with and defines a pump chamber 114 of substantially circular cross-section. A valve housing 116 of substantially circular cross-section extends from the lower end of the pump chamber 114 and provides an opening 117 through which the chocolate syrup is discharged.

- 10 A resilient inverted cup-shaped valve 118 is seated in the opening 117 of the lower or outlet end of the valve housing 116 and is responsive to the fluid pressure forces created by the piston arrangement 112 to permit the flow of chocolate syrup through the opening 117.
- 15 The valve 118 includes an annular shoulder 119 which seats against the free lower end of the valve housing 116 to provide a seal. Upon the application of a pressure force thereon, the cup-shaped valve yields, as shown in FIG. 17, so that fluid is free to flow through 20 the annular passage created between the shoulder 119 and the end of the valve housing 116. The valve 118 is mounted in the valve housing 116 by a diametrically extending brace 121, the ends of which abut against the opposed inner walls of housing 111, and having a 25 downwardly and axial depending stud pin 122 which seats in pocket 120 of the valve 118. The brace 121 is also provided with an enlarged medial portion 121'.

The piston head assembly 112 includes a disk or connecting head 123 fixed to the lower end of a piston-rod 124. The head 123 is in the form of a disk of substantially the same diameter as the pump chamber 114 so as to be snugly slidably therein. A slide head in the form of a circular plate 126 is lengthwise slidable on an axial headed pin 128 fixed to the lower end of the shaft. The slide plate 126 is adapted to prevent passage through angularly spaced apertures 129 in the disk 123 during downward movement of the piston head assembly 112, as shown in FIGS. 16 and 17. During upward movement of the piston head assembly 112, the force of the chocolate syrup in the chamber 113 forces the slide plate 126 to the head of the pin in the position shown in FIG. 18 spaced from the disk 123 so that the chocolate is free to flow through the apertures 129 into the pump chamber 114. Thus, when the piston head assembly 112 reaches its upper limit of travel, the pump chamber 114 is filled with the chocolate syrup for mixing with a diluting liquid such as hot water.

The volume of concentrated chocolate for mixing with the liquid is determined by the upper limit of travel of the piston head assembly 112 and this is achieved by the same adjusting and actuating structure 27 as shown and described in connection with the embodiment of FIGS. 1-8. The travel may be selectively adjusted to achieve the desired volume of chocolate by adjustment of the sleeve 58 to increase or decrease the angular turning of the rock shaft 64 which causes a corresponding increase or decrease in the length of arc of the rock arm 76 at the connection with the piston rod 124. The length of the arc corresponds to the length of travel of the piston assembly 112.

Upon downward movement of the piston assembly, the slide plate 126 overlies the apertures 129 so that the pressure created on the chocolate syrup in chamber 114 and on the upper surface of the valve 118 causes the resilient cup valve 118 to be forced downwardly and the chocolate syrup to flow through the opening 117, as shown in FIG. 17. The syrup flows onto the con-

ical plate 82 and is mixed or at least pre-mixed with water from the nozzle 84. The pre-mixed chocolate syrup and water flows through the opening 82 through the outlet 80 into a cup as in the main embodiment.

In both embodiments, the water from nozzle 84 is introduced to plate 81 at a tangent so that as the syrup is introduced towards said plate, a swirling admixing is accomplished before the admixture flows through the aperture 82.

The electrical system is substantially the same as shown in U.S. Pat. Nos. 3,159,190 and 3,382,897, both of which are owned by the assignee of this application.

Although but two specific embodiments of this invention are shown and described, it is to be understood that the numerous details shown may be altered or omitted without departing from the spirit of this invention as defined by the following claims.

I claim:

1. A dispensing device comprising a storage tank for a concentrated syrup, a pump located adjacent the bottom of said storage tank, said pump including a pump chamber communicating with the interior of said storage tank through the base, a pressure responsive valve at one end of said pump chamber, a piston means movable in said pump chamber between a position adjacent said pressure responsive valve and a position spaced from said pressure responsive valve to define a volume for the concentrated syrup, said piston means including a piston rod connected to said piston and extending through said storage tank, a rock arm connected to one end of a rock shaft, means connecting said piston rod to said rock arm a fixed distance from said rock shaft, a rock arm connected to the other end of said rock shaft and located outside of said storage tank, a sleeve axially slidable on said rock arm connected to the other end of said rock shaft, a connecting rod fixed at one end to said sleeve and connected at the other end to eccentric means for imparting reciprocating movement to said connecting rod, and means for fixing said sleeve against axial movement along said rock arm connected to the other end of said rock shaft thereby to selectively vary the angular rocking movement of said rock shaft

and thereby the volume defined by said piston in said chamber.

2. The invention as defined in claim 1 wherein said piston means comprises a connecting head fixed to said linkage means, and a slide head movable into engagement with said connecting head during movement of said piston means away from said pressure responsive valve and movable into spaced relationship with said connecting means, said piston means having opening means providing communication between said pump chamber and said storage tank, said opening means being closed when said slide head is in engagement with said connecting head and being open when said slide head is in spaced relation to said connecting head.

3. The invention as defined in claim 3 wherein said opening means are located through said slide head and said connecting head cutting off flow through said openings.

4. The invention as defined in claim 3 wherein said opening means are located in said connecting head and said slide plate cuts off flow through said openings.

5. The invention as defined in claim 1 wherein said connecting rod means includes means automatically adjusting the length thereof between said slideable sleeve and said eccentric driving means when said slideable sleeve is selectively positioned on said first rock shaft.

6. The invention as defined in claim 5 wherein said slideable sleeve is selectively positioned frictionally by means including a plate, and an adjustment lever means pivotally connected between said adjustment plate and said slideable sleeve.

7. The invention as defined in claim 1 wherein said dispensing means includes mixing chamber means, said mixing chamber including a bowl, having a conical bottom wall, and a nozzle containing mixing liquid for mixing with said concentrated syrup directed on said mixing plate tangentially; and wherein said conduit through which said syrup is discharged is aligned above said conical plate so that the concentrated syrup is discharged thereon for mixing with said mixing liquid.
